[57] **CLAIM**

The ornamental design for a light fixture, as shown and described.

DESCRIPTION

FIG. 1 is a perspective view of a light fixture embodying my new design;

FIG. 2 is a bottom plan view thereof;

FIG. 3 is an elevational view thereof;

FIG. 4 is a cross-sectional elevational view thereof; and
FIG. 5 is a top plan view thereof.

The outer tubular member of my new design is translucent, while the inner frusto-conical member is opaque.

fig. 1
